UNITED STATES PATENT OFFICE.

LOUIS WITRY, OF WATERLOO, IOWA, ASSIGNOR TO THE WATERLOO GASOLINE ENGINE COMPANY, OF SAME PLACE.

IGNITER FOR EXPLOSIVE-ENGINES.

SPECIFICATION forming part of Letters Patent No. 655,289, dated August 7, 1900.

Application filed December 16, 1899. Serial No. 740,542. (No model.)

To all whom it may concern:

Be it known that I, LOUIS WITRY, a citizen of the United States, residing at Waterloo, in the county of Black Hawk and State of Iowa, have invented certain new and useful Improvements in Igniters; and I do hereby declare the following to be a full, clear, and exact description of the invention, such as will enable others skilled in the art to which it appertains to make and use the same.

My invention relates to improvements in igniting devices for gas, oil, and other explosive and internal-combustion engines; and it consists in the novel means employed for operating the igniting device when starting the engine.

The object of my invention is to insure the prompt ignition of the explosive charge in the engine-cylinder when first starting the engine and to make it possible to operate the igniting device effectively independent of the position of the piston. This object is attained in the invention herein described and illustrated in the drawings, which accompany and form a part of this specification, in which the same reference-numerals indicate the same or corresponding parts, and in which—

Figure 1 is a central vertical section of the cylinder of an engine, showing the igniting device in elevation. Fig. 2 is a transverse vertical section of the engine-cylinder, showing the igniting device in elevation as viewed from the left of Fig. 1; and Fig. 3 is a top view of the igniting device.

In the igniting device herein illustrated and described I employ in addition to the usual contact points or pieces and means for alternately making and breaking contact between such contact-points automatically as the engine operates a hand-operated and spring-retracted hammer, adapted when drawn forward by the hand and then released to strike a member connected to the movable contact-piece and by its impact to break the contact between said contact-pieces sharply, thus producing an effective spark for igniting an explosive charge in the engine-cylinder.

In the drawings, 1 is a pin, forming the fixed and insulated contact-piece. It is supported by an insulating-bushing 2. 3 is the movable electrode. It has two branches or arms which

preferably are substantially at right angles. Because of its form it is termed a "crow-foot." It is carried by a spindle 4, revolvably mounted in a bushing 5. One arm of the crow-foot is beveled and is adapted to make contact with the fixed electrode 1. The other arm of the crow-foot is in the path of a stud 6, carried by the piston 7 of the engine. Said stud encounters the crow-foot when the piston has almost reached the end of its stroke and revolves it and its spindle 4, breaking contact between the crow-foot and the pin 1, and so causing the formation of a spark by which an explosive charge in the cylinder may be ignited.

Upon its outer end the crow-foot spindle 4 is provided with an arm 8, to which is connected a spring 9, also connected to a post 10 and tending to hold the contact-pieces in contact.

Upon the spindle 4 is mounted loosely a projecting lever 11, termed a "hammer." This hammer is adapted to make contact with the arm 8, and a spring 12, opposing spring 9, but slightly weaker, tends always to hold hammer 11 and arm 8 in contact.

During the operation of the engine the piston 7 of the engine when near the rear limit of its stroke brings its stud 6 into contact with the crow-foot, causing the latter to break contact with the pin 1, thus producing a spark, which will ignite an explosive charge in the cylinder. When the piston moves forward again, the spring 9 moves the crow-foot back into contact with the fixed contact-piece 1.

In starting the engine an explosive charge is drawn into the engine-cylinder by turning the fly-wheel by hand forward from the rear dead-center through half or nearly half a revolution in the ordinary manner. To compress the charge, the fly-wheel may be turned onward to complete the revolution, the igniting device being operated automatically; but it is better to compress the charge by moving the fly-wheel backward instead of forward until the end of the stroke is nearly reached. The hammer 11 may then be pulled forward or away from the lever 8, and when released is drawn backward violently by its spring 12, so that the hammer is caused to strike the arm 8 and by its impact to part the contact-

pieces, producing a spark. The contact between said contact-pieces is broken more quickly by means of the hammer than when the fly-wheel is rotated by hand far enough forward or back to break the contact, and thus a sharper spark is produced. Also because the springs 9 and 12 are nearly balanced the hammer when thus operated does not come to rest at once, but vibrates back and forth three or four times, producing a succession of sparks, which insure the ignition of the charge in case for any reason the first spark did not suffice for that purpose.

I have found that whereas a simple parting of the contact-points by hand when starting the engine often fails to ignite the charge the use of the hammer for that purpose gives far more effective results and insures the ignition of the charge at the time desired.

Having thus completely described my invention, what I claim, and desire to secure by Letters Patent, is—

1. In an igniting device for explosive and internal-combustion engines, the combination, with a circuit making and breaking device, and means operated by the engine in its movement to operate the same automatically, of an independent spring-retracted member, adapted, when released after the spring has been placed under tension, to encounter an operating member of said circuit making and breaking device, and by the force of its impact to operate the same.

2. In an electric igniting device for explosive and internal-combustion engines, the combination with contact-pieces, one fixed and the other movable, relatively to each other, a spring adapted to move the movable contact-piece toward the stationary contact-piece, and means operated by the engine in its movement to separate the contact-pieces

to produce a spark, of an independent spring-retracted member, adapted, when released after the spring thereof has been placed under tension, to encounter the movable contact-piece and by force of its impact operate the same.

3. In an igniting device, the combination, with contact-pieces, one of which is movable, and a spring for holding said movable contact-piece normally in one position, of a spring-retracted hammer, the spring of which opposes, but is weaker than, the spring of the movable contact-piece, said hammer being adapted, when drawn forward and then released, to encounter the movable contact-piece and by the force of its impact to operate the same.

4. In an igniting device for internal-combustion engines and the like, the combination, with a fixed contact-pin and a movable crow-foot contact-piece, both located within the combustion-space of the engine, the crow-foot being mounted upon a revoluble spindle having an external projecting arm, and being arranged to be actuated by the piston of the engine, of a spring tending to hold said contact-pieces in contact normally, and a spring-retracted hammer, the spring of which opposes, but is weaker than, the spring of the movable contact-piece, said hammer being adapted, when drawn forward and then released, to encounter the arm on the crow-foot spindle, and by the force of its impact to separate the contact-pieces.

In testimony whereof I affix my signature in the presence of two witnesses.

LOUIS WITRY.
